Primary Examiner — Karen E Eldridge Powers(74) *Attorney, Agent, or Firm* — Wood, Herron & Evans, L.L.P.(57) **CLAIM**

The ornamental design for a cosmetics brush, as shown and described.

DESCRIPTION

FIG. 1 is a front-top perspective view of a cosmetics brush showing the new design.

FIG. 2 is a front-bottom perspective view thereof;

FIG. 3 is a left-side elevation view thereof;

FIG. 4 is a right-side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines in the figures show portions of the cosmetics brush which form no part of the claimed designs.
